Primary Examiner — Thomas Johannes(74) *Attorney, Agent, or Firm* — Richard A. Koske; Foster Pepper PLLC(57) **CLAIM**

I claim the ornamental design for the ice cream container, as shown and described.

DESCRIPTION

FIG. 1 is a front perspective view of an ice cream container, showing my new design;

FIG. 2 is a front elevation view thereof;

FIG. 3 is a left side elevation view thereof;

FIG. 4 is a top plan view thereof;

FIG. 5 is a bottom plan view thereof;

FIG. 6 is a right side elevation view thereof;

FIG. 7 is a back elevation view thereof; and,

FIG. 8 is a front perspective view thereof with the top open.
